2 SHEETS—SHEET 2.

UNITED STATES PATENT OFFICE.

WILLIAM J. McGOVERN, OF PEEKSKILL, NEW YORK

CONVEYER FOR UNLOADING VESSELS, BARGES, AND THE LIKE

1,283,838.

Specification of Letters Patent.

Patented Nov. 5, 1918.

Application filed April 8, 1918. Serial No. 227,347

To all whom it may concern:

Be it known that I, WILLIAM JOHN Mc-GOVERN, a citizen of the United States, and a resident of the village of Peekskill, county 5 of Westchester, and State of New York, have invented certain new and useful Improvements in Conveyers for Unloading Vessels, Barges, and the like, of which the following is a specification accompanied by 0 drawings.

My invention relates to conveyers but more particularly to conveyers for unloading vessels, barges and the like, although my invention may be used in any connection 15 to which it is applicable.

One of the objects of my invention is to provide a means for unloading a vessel or barge with economy, rapidity and convenience, and for delivering the load at a desired point, above or below the deck-level, and in front of or on either side of the boat.

Further objects of my invention will hereinafter appear; and to these ends my invention consists of apparatus for carrying out the above object embodying the features of construction, arrangement of parts, and combination of elements having the general mode of operation substantially as hereinabove fully described and claimed in this specification and shown in the accompanying drawings in which Figure 1 is a longitudinal sectional view of a vessel constructed in accordance with my invention, with the apparatus in position for unloading, and with the position of the apparatus when not in use indicated by the dotted lines: Fig. 2 is a transverse sectional view thereof taken on the broken line 2, 2, Fig. 1, and as seen looking at that figure from the left toward the right hand side of the drawings in the direction of the arrows: Fig. 3 is a transverse sectional view thereof taken on the broken line 3, 3, Fig. 1, and as seen looking at that figure from the right toward the left hand side of the drawings in the direction of the arrows: Fig. 4 is a longitudinal view of my apparatus; and Fig. 5 is a detailed view in perspective of a roller at the base of the inclined movable frame work carrying the conveyer belt.

Similar numerals refer to similar parts throughout the several views.

Referring now to the drawings in detail and particularly to Fig. 2, the structures 66 are inwardly inclined false decks. Refer-

ring now particularly to Fig. 1, the structures 7 7 are hoppers; 8 8 are means for closing hoppers; 9 is a single continuous conveyer belt on an inclined movable framework with means for making the same more readily movable and preferably a roller 10 on the lower end thereof and any kind of an extension arm on the upper end thereof and preferably a sliding extension 11; 12 12 are hinged guiding chutes attached to and on the top of the framework 9 and 13 13 are means for locking the hinged chutes in position; 14 is means for changing the angle of inclinatiton of the framework by moving the framework and changing the point of support thereon and preferably a bearing wheel with a smooth rim supporting the upper end of the framework 9 on the underside thereof, and a geared edge meshing into gear teeth 15 along the outside of framework 9; 16 is a dog attachment on the bearing wheel 14; 17 17 are means for locking the framework 9 after it has been moved forward into position for operation; 18 18 are means for moving the sliding extension 11 into position for operatiton and preferably are a block and fall; 19 19 are means for locking the sliding extension 11 after it has been moved into position for operation; 20 20 are braces hinged on the sides of the framework 9; 21 21 are two folder pulleys on the underside of the sliding extension 11 with the returning belt running between them; 22 is means for applying power to the conveyer belt and preferably a shaft in the power pulley; 23 is any suitable source of power; and 24 is a power pulley on the same shaft as the bearing wheel 14.

When the power is applied at the power 95
pulley 24 and the bearing wheel 14 is turned,
the gear teeth 15 mesh therein and move the
framework 9 forward. The framework 9
is continuously balanced upon the smooth
rimmed portion of the bearing wheel 14 and
is continuously supported at the base by the
roller 10 which moves forward in conformity
with the movement of the gears. After
the framework 9 has been moved forward
as described it is locked in position by the 105
braces 17 17 and is further and automatically
secured by the dog attachment 16.
After the framework 9 has been locked into
position for operation, and the braces there-
on 20 have been set, the sliding extension 11
is raised by the block and fall or other
means 18 and locked into position by the 110

braces 19. The hinged guiding chutes are then raised and locked by means of the braces 13, and the power is applied at shaft in the power pulley 22.

5 When the power is applied at the shaft in the power pulley 22, and the hoppers are opened, the cargo is conveyed by a single continuous conveyer belt to the upper end of the sliding extension 11 whence it may be 10 directed through a chute to any desired point.

Obviously some features of my invention may be used without others and my invention may be embodied in widely-varying 15 forms. It is also obvious that using a square shaft and a sleeve coupling between the source of power 23 and the power pulley 22, the conveyer belt may be turned by a direct drive.

20 It is also obvious that by constructing the support for the bearing wheel 14 in such a way that the bearing wheel may be raised or lowered as on a jack, a still more variable angle of inclination of the belt and frame 25 work 9 may be obtained.

I am aware that prior to my invention vessels have been devised with inclined sides and discharge hoppers adapted to discharge the cargo by means of two or more immovable 30 conveyer belts or by means of conveyer belts traveling at different and fixed or constant angles of inclination and I make no claim hereinafter broad enough to include such structures: but

35 I claim:

1. In a cargo conveyer having a hopper dependent into a chamber below a floor provided with an opening to permit passage into said chamber of an endless conveyer 40 belt structure and dimensioned to permit flatwise adjustment of such structure in the opening, the combination of an endless-belt conveyer structure provided with rollers at its inward corners; a down holding and 45 guide-forming means for the rollers; means within the chamber for supporting the conveying-belt structure between its ends and for raising and lowering its discharging end; and belt-driving means.

2. In the structure of claim 1, said supporting means comprising jack mechanism provided with a transverse shaft having end rollers for supporting the conveyer structure outwardly of its inner corner rollers and the down-holds. 50

3. In the structure of claim 1, said supporting means comprising jack mechanism provided with a transverse shaft having end rollers for supporting the conveyer structure outwardly of its inner corner rollers 60 and the down-holds, said conveyer structure being provided with a lengthwise-extending rack, and said shaft being provided with a spur gear meshing with the rack, the down-holds extending from a hull side inwardly 65 and forming with the hull floor transverse guideways for the corner rollers.

4. In the structure of claim 1, the conveyer structure having lengthwise-extending racks and said means within the chamber for supporting and raising and lowering the conveyer structure comprising a pair of spur gears one for each rack, each spur gear having a disk extension forming a bearing for a side bar of the conveyer structure. 70 75

5. In the structure of claim 1, the dependent hopper of the cargo conveyer and the endless belt conveyer structure provided with a hinged chute constructed to be raised 80 into position for reception within its walls of the dependent hopper walls.

6. In the structure of claim 1, the endless belt conveyer structure with a foldable chute provided with a back and two side walls, 85 and being foldable on the conveyer structure to bring its back in a position opposed to the conveying portion of the belt and its sides at the sides of said structure, and means for supporting said chute in an up- 90 standing position.

In testimony whereof I have signed this specification in the presence of two subscribing witnesses, this sixth day of April, 1918.

WILLIAM J. McGOVERN.

Witnesses:

WILLIAM J. REDMOND,
FREDERICK F. HALL.
